REENFORCEMENT FOR ROUND REACTION TOWERS FOR THE MANUFACTURE OF
SULPHURIC ACID

Application filed April 21, 1931, Serial No. 531,838, and in Denmark April 24, 1930.

In the manufacture of sulphuric acid round reaction towers are used, the outer wall of which consists of tiles which are covered outside with a mantle of lead, which is 5 to prevent the escape of gases or acid.

This mantle must lie tightly against the tile wall and is pressed against the same by means of an exterior reenforcement. For this purpose there has hitherto been used 10 an armature or reenforcement consisting of vertical wooden laths which are pressed against the lead mantle by means of horizontal iron bands.

Such reenforcing has the drawback that 15 the wooden laths interfere with the cooling by the outer air of the surface of the leaden mantle, and it has also the drawback that acid which may have found its way between the tile wall and the leaden mantle, owing 20 to the spaces between the wooden laths, may spread between the wall and the mantle on the inner surface of the same, which may cause a corrosion of the lead and even a fracture of the leaden mantle if the liquid pressure 25 sure becomes sufficiently great. As such reaction towers are rather high and the acid has a considerable specific gravity the hydrostatic pressure can, if a vertical channel of acid be formed between the tile wall and the leaden mantle reach a value at the foot of the leaden mantle which the leaden mantle cannot sustain so that it breaks or leaks.

Therefore, the present invention contemplates pressing the leaden mantle tightly 35 against the tile wall at as many places as possible and along horizontal lines in order to prevent the formation of such vertical channels. The invention more particularly provides a reenforcement of the leaden mantle by means of vertically arranged metal cables or belts of metal wire-gauze or netting, whereby the above named disadvantages are obviated.

In the drawing Figure 1 shows diagrammatically part of a leaden mantle with a re-enforcement according to the invention.

Figure 2 is a detail on a larger scale and Figure 3 is a modification.

As it will appear from Figure 1 there is 50 used a belt of metal wires 1, which by vertical

wires 2 are connected so as to form a wire gauze. A number of such belts are used at suitable mutual intervals. The wires preferably have a diameter of about 5 mm. and the distance between the vertical wires preferably is about 60-100 mm. The distance between the wires 2 is preferably 150 mm. and the total breadth of a belt is preferably 0.5-1 m.

The wire gauze is made and applied in such a manner that the smooth side is turned towards the leaden mantle, the wires 1 and 2, as indicated in Figure 2 and 3 and 4, being offset in such a manner that there are formed substantially no protruding parts which can 65 be pressed into the lead. The securing and tightening of the belt is effected by means of angle-irons 6 and bolts 7, as appears in Figure 1.

In the modification shown in Figure 3 a 70 number of independent cables or wires 8 are laid around the reaction tower at suitable distances, and each individual cable is tightened by means of an ordinary rigging screw 9 with right- and left-handed threads.

By the reenforcement of reaction towers by such cables or belts of wire-gauze the leaden mantle is pressed against the tile wall without the use of heat-insulating substances, and as the lines along which the contact takes 80 place are horizontal and at a small mutual distance no gap can exist between the tile wall and the leaden mantle to occasion fracture of the leaden mantle.

Having fully described our invention we 85 claim as new and desire to secure by Letters Patent:

1. Reenforcing means for reaction towers for manufacturing sulphuric acid of the type having an inner tile wall and an outer leaden mantle in contact therewith, comprising a plurality of closely spaced metal bands, each of the bands being provided with a turnbuckle adapted to be tightened to press each of the bands individually against the leaden mantle to thereby press the latter against the said tile wall along horizontal lines.

2. Reenforcing means for reaction towers of the type having an inner tile wall and an outer leaden mantle in contact therewith,

comprising a unitary belt of wire netting and means for tightening the said belt into contact with the leaden mantle to thereby press the latter into intimate contact with the said inner tile wall.

3. Reenforcing means for reaction towers of the type having an inner tile wall and an outer leaden mantle in contact therewith, comprising a belt of wire netting in contact with the outer surface of the mantle, said netting being substantially free from protruding parts on the side contacting with the said leaden mantle, and means for tightening the said belt around the leaden mantle to there-
15 by press the latter into close contact with the said inner tile wall.

4. A reaction tower for use in the manufacture of sulphuric acid, comprising a tile wall, a leaden mantle in contact therewith, and means for pressing the said mantle into close contact with the said tile wall along horizontal lines sufficiently to prevent the formation of interstices of any substantial height, depth or width between the mantle and the tile wall.

In testimony whereof we have affixed our signatures.

CARL LUDVIG EMIL JENSEN.
